UNITED STATES PATENT OFFICE.

ISAAC RUSHWORTH, OF JAMESTOWN, NEW YORK.

DABBING-BRUSH APPARATUS FOR WOOL-COMBING MACHINES.

SPECIFICATION forming part of Letters Patent No. 642,160, dated January 30, 1900.

Application filed March 6, 1899. Serial No. 707,936. (No model.)

To all whom it may concern:

Be it known that I, ISAAC RUSHWORTH, a citizen of the United States, residing at Jamestown, in the county of Chautauqua and 5 State of New York, have invented a new and useful Dabbing-Brush Apparatus for Wool-Combing Machines, of which the following is a specification.

This invention relates to dabbing-brush apparatus for wool-combing machines; and the 10 object of the invention is to provide a construction wherein the parts can be assembled with rapidity and manufactured at a low cost, and the apparatus is in the nature of an 15 improvement upon that set forth in Letters Patent No. 525,429, granted to me September 4, 1894.

With these ends in view the invention consists in the novel combination of elements and 20 in the construction and arrangement of parts which will be hereinafter more fully described and claimed.

To enable others to understand the invention, I have illustrated the preferred embodiment thereof in the accompanying drawings, forming a part of this specification, and in which—

Figure 1 is a side elevation, partly in section, showing the elements of my invention 30 in their correlative positions. Fig. 2 is a front elevation with a portion of the casing removed for the same purpose. Fig. 3 is a horizontal section taken in the line 3-3 of Fig. 1.

Similar reference characters denote corresponding parts in each of the several views. 35 Certain of the operative parts of the apparatus are inclosed within the casing C, which consists of two parts, as 2 and 3, each in the form of a plate. The back plate 3 is provided 40 with arms 4, located at suitable points in the height thereof and concaved to fit against the correspondingly-shaped face of the vertical pillar or standard 5, bolts being provided to hold the plate 3 in place. The pillar 5 is hollow and incloses the vertical driving-shaft 6, which can be connected in some suitable manner with the driving-pulley 7, secured to the eccentric brush-operating shaft 8. These 45 parts may be connected in the manner shown 50 in the Letters Patent heretofore mentioned.

The plates 2 and 3 are separated by a comparatively wide space, in which certain of the

operative parts are inclosed, and the plate 2 is provided with a web 9, extending entirely around the outer edge thereof and provided 55 with an inturned flange 10, which can be bolted or otherwise secured to the face of the back plate 3.

The shaft 8 is adapted to turn in bushings 14, fitted in transverse openings 15 in the 60 plates 2 and 3, the latter having annular flanges 16' placed against the adjacent faces of hubs 16, surrounding the bearing-openings, said bushings being held in place through the medium of bolts or screws 15", passed there- 65 through and into the hubs 16.

Keyed or otherwise secured to the shaft 8 is a pulley 7 for rotating the said shaft, and, as shown in dotted lines, a key is operatively interposed between a part of the pulley and 70 shaft for an obvious purpose and held against displacement by means of a nut 17, engaging the threaded end of the shaft.

The shaft 8 is recessed, as at 30, and therein on said shaft is an eccentric 12 within the 75 plane of the adjacent part of the shaft and which is less in width than the recess to provide opposite grooves 26 and 26', the remaining part of said eccentric being a radially-extending web 12'.

Upon the eccentric 12 is an eccentric-strap 23, carried by an eccentric-arm 20 and having an inwardly-directed flange 31 at one edge which bears against the adjacent edge of the said eccentric and also enters the groove 26 85 of the recess 30 in the shaft 8. At the opposite side of the eccentric a retaining-ring 22 is applied in the groove 26', held in place by means of screws passed therethrough into the strap 23.

To provide for the insertion or application of the strap 23 relatively to the eccentric, the shaft 8, as previously indicated, is recessed adjacent the eccentric 12, as at 30, to receive a filling-block 31, the outer face of which is 95 curved to agree with the curvature of the shaft. This filling-block constitutes, in fact, a part of the shaft and rotates within the inner bushing 14, being held in place by screws or other fastening devices and shouldered at 100 its outer end, as at 32, to fit against its inclosing bushing, the said shouldered end being in proximity to the annular flange of the eccentric-strap, which projects into the por-

tion 26 of the said recess 30. The outer end of the eccentric-arm 20 is provided with a bearing-opening 35 to receive a pivot-bolt 36, which extends through a longitudinal slot 37 in the cap-plate 2 and also through a pivot or journal opening in the upper end of a slide 37', which is reciprocated between the guide-strips 18 on the front side of the face-plate. The slide 37' is provided at its lower end with 10 the usual brush.

The purpose of the casing C is to protect the bearing parts of the apparatus as far as practicable, and it contains oil for the purpose of lubricating the parts, and to prevent 15 the escape of the oil as the eccentric-arm rises splasher-guards 40 are provided and located one above the other, said guards consisting of curved plates or flanges extending inwardly from the front plate 2 and the inner 20 edges of which are located in proximity to the eccentric-arm 20, thereby to prevent the spashing of oil through the opening 37 on the reciprocation of the eccentric-arm.

The plate 2 at the upper side thereof is provided with a depending internal portion 42, having a rabbeted guideway 43 to receive a correspondingly-shaped head 44 of the connecting bolt or pivot 35, and the length of this portion 42 slightly exceeds the length of 30 the working stroke of the eccentric-arm, with which said pivot is connected, whereby the upper end of the arm will be properly guided throughout the complete stroke thereof.

Changes in the form, proportions, size, and 35 minor details of construction within the scope of the invention may be resorted to without sacrificing any of its advantages.

Having thus described the invention, what is claimed as new is—

40 1. In an apparatus of the class specified, the combination of a shaft having an eccentric partially within the plane of the adjacent part thereof, a driving member for the shaft, an eccentric-arm having an eccentric-strap surrounding the said eccentric and provided with an inwardly-directed annular flange fitted in the shaft to one side of the eccentric, means for connecting said eccentric-strap and eccentric, a slide provided with a brush, and a bolt connecting said eccentric-arm and slide.

45 2. In an apparatus of the class specified, the combination of a shaft having an eccentric and provided with a driving member, an eccentric-arm having an eccentric-strap surrounding the eccentric and having an inwardly-directed annular flange fitted in a portion of the shaft adjacent the eccentric, means for fastening the eccentric-strap and eccentric, a slide provided with a brush, a bolt connecting said eccentric-arm and slide, and a casing adapted to contain a lubricant and also inclose said eccentric and eccentric-arm and having an opening through which 50 said bolt passes.

55 3. In an apparatus of the class specified, the combination of a shaft having an eccentric a

reciprocating arm provided with an eccentric-strap having an inwardly-directed annular flange fitted in a portion of said shaft, means 70 for connecting said strap and eccentric, a slide provided with a brush, a bolt connecting said arm and slide, and a casing adapted to contain a lubricant and also inclose said eccentric and arm and having an opening 75 through which said bolt passes, the casing having one or more guard-flanges extending inwardly therefrom, with the edges in proximity to the arm and serving to prevent the escape of oil.

80 4. In an apparatus of the class specified, the combination of a shaft having an eccentric and provided with a driving member, an arm carrying an eccentric-strap surrounding the eccentric and provided with an inwardly-directed annular flange fitted in a portion of the shaft, means for connecting the eccentric-strap and eccentric, a filling-block disposed in a socket in the said shaft, adjacent the inwardly-directed annular flange and having 85 its outer surface curved to conform to the curvature of the shaft, a slide provided with a brush, and a bolt connecting said eccentric-arm and slide.

90 5. In an apparatus of the class specified, the combination of a shaft having an eccentric and provided with a driving member, an eccentric-arm carrying an eccentric-strap surrounding the eccentric and provided with an inwardly-directed annular flange fitted in a portion of the shaft, means for connecting 95 said eccentric-strap and eccentric, a filling-block secured in a socket in the shaft adjacent the said eccentric-strap flange, a casing consisting of front and back plates separated by a space in which said eccentric is located and provided with bushings for sustaining 100 said shaft, one of the bushings inclosing said filling-block, a slide, a bolt connecting the slide and eccentric-arm and extending through an opening in the casing, and a guide operable in connection with the head of said bolt.

105 6. In an apparatus of the class specified, the combination of a shaft having an eccentric and provided with a driving member, an eccentric-arm carrying an eccentric-strap surrounding the eccentric and provided with an inwardly-directed annular flange snugly fitted in a portion of said shaft, means for connecting 110 said eccentric-strap and eccentric, a filling-block secured in a socket in the shaft, adjacent the eccentric-strap flange, a casing consisting of front and back plates, one of said plates having a web extending around the same which is flanged and secured to the other 115 plate, a slide, a bolt connecting said slide and eccentric-arm and extending through a slot in the casing, and a guide for the head of the bolt having a rabbet to receive the correspondingly-shaped portion of the bolt-head.

120 7. In an apparatus of the class specified, the combination of a shaft having an eccentric and provided with a driving member, an eccentric-arm carrying an eccentric-strap sur-

rounding the eccentric and provided with an inwardly-directed annular flange snugly fitted in the said shaft, means for connecting said eccentric-strap and eccentric, a filling-block 5 secured in a socket in the shaft, adjacent to the eccentric-strap flange, a casing consisting of front and back plates, one of said plates having a web extending around the same, which is flanged and secured to the other plate, 10 a slide, a bolt connecting said slide and eccentric-arm and extending through a slot in the casing, a guide for the head of the bolt having a rabbet to receive the correspondingly-shaped portion of the bolt-head, and two super-

posed curved flanges on the inside of the front 15 plate of the casing, the inner edges of said flanges being adjacent to the eccentric-arm and said flanges constituting guards to prevent the escape of oil through the slot in the casing.

In testimony that I claim the foregoing as my own I have hereto affixed my signature in the presence of two witnesses.
